UNITED STATES PATENT OFFICE.

WILLIAM H. ROBBINS, OF SPRINGFIELD, AND WALTER C. LOHMAN, OF DAYTON, OHIO,
ASSIGNORS TO THE WILLIAMS COMPANY, OF LONDON, OHIO, A CORPORATION OF
OHIO.

STEEL-WOOL ARTICLE FOR CLEANSING AND ABRADING PURPOSES.

Application filed January 3, 1927. Serial No. 158,568.

Our invention relates to steel wool holders. The object of our invention is to provide a cheap steel wool holder so that the wool may be held without soiling the hands while it is 5 being used for cleansing and abrasive purposes.

Referring to the drawings:

Figure 1 is a side elevation of our holder; Figure 2 is a section of our holder with a

10 pad mounted thereon; and

Figure 3 shows a side elevation of our holder using heavily compressed felt.

Referring to the drawings in detail, 1 is a handle, preferably of wood, having a slightly 15 enlarged head 2, upon which is mounted one or more pads of felt 3 attached by the screw or nail 4 to the end of the handle 1. The sides of the felt pad 3 are rough and expose the fibers composing the felt pad.

20 In Figures 1 and 2, a coarse form of felt having strands 5 is provided, such felt being that usually used in paper machines. It provides a coarse surface for attaching the steel wool pad 6, which is usually cup-shaped, having walls extending up around the sides of the felt pad. One or more pads may be used according to the depth of the walls of the steel wool pad.

25 For some types of wool, we find that the finer grades of felt, as shown in Figure 3, which do not have such coarse fibers, are preferable.

It will be understood that we desire to comprehend within our invention such modifica-

tions within the scope of the claims as may be 35 necessary to adapt it to varying conditions and uses.

Having thus fully described our invention, what we claim as new and desire to secure by Letters Patent is:—

1. An article of the character described comprising a supporting handle, a pad of felt on the end thereof, and a cup-shaped pad of steel wool engaging the said felt.

2. An article of the character described 45 comprising a supporting handle, a pad of felt on the end of the said handle and secured thereto, the side walls of the pad being roughened, and a cup-shaped steel wool pad engaging the roughened fibrous side walls of the 50

3. An article of the character described comprising a handle, a pad of felt provided with exposed sides, and a cup-shaped steel wool pad engaging the sides of the said felt, 55 the said felt being of larger diameter than the said handle adjacent the point of attachment.

4. An article of the character described comprising a handle, a felt pad secured to the handle, the said pad consisting of coarse 60 fibrous felt exposed at the sides thereof, a cup-shaped steel wool pad having the inner wide walls thereof engaging with the said coarse fibers of the felt pad.

In testimony whereof, we affix our signatures.

WILLIAM H. ROBBINS.
WALTER C. LOHMAN.
